[Term of patent 3½ years.]

To all whom it may concern:

Be it known that I, GEORGE W. PIGGOTT, of New York city, county and State of New York, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The figure A is a large irregular figure, partly surrounded by border, and profusely ornamented by floral embellishments. B is an irregular figure, also richly ornamented. The figure D is approximately L-shaped, and

E is zigzag-shaped. The figures G D B F E partly surround the figure A.

The carpet is embellished by a number of stripes, scrolls, and smaller figures. The several figures constituting the design are ornamented by rich floral design and oriental patterns.

I claim as my invention—

1. The design for a carpet, consisting of the figures A B, substantially as shown.
2. The design for a carpet, consisting of the figures A G D, substantially as shown.
3. The design for a carpet, consisting of the figures B F E, substantially as shown.
